(57) **CLAIM**

The ornamental design for a set of earphone pens and case, as shown and described.

DESCRIPTION

FIG. 1 is a first perspective view of a set of earphone pens and case showing our new design;

FIG. 2 is a second perspective view of the set of earphone pens and case showing a cover separating from the case;

FIG. 3 is a third perspective view of the set of earphone pens and case showing only the two earphone pens with cap;

FIG. 4 is a perspective view of the case;

FIG. 5 is a front view of the case;

FIG. 6 is a rear view of the case;

FIG. 7 is a left side view of the case;

FIG. 8 is a right side view of the case;

FIG. 9 is a top plan view of the case;

FIG. 10 is a bottom plan view of the case;

FIG. 11 is a perspective view of the cover;

FIG. 12 is a front view of the cover, with the opposing rear side being a mirror image thereof;

FIG. 13 is a left side view of the cover, with the opposing right side being a mirror image thereof;

FIG. 14 is a top plan view of the cover;

FIG. 15 is a bottom plan view of the cover;

FIG. 16 is a perspective view of the earphone pen without the cap;

FIG. 17 is a front view of the earphone pen without the cap;

FIG. 18 is a rear view of the earphone pen without the cap;

FIG. 19 is a left side view of the earphone pen without the cap;

FIG. 20 is a right side view of the earphone pen without the cap;

FIG. 21 is a top plan view of the earphone pen without the cap;

FIG. 22 is a bottom plan view of the earphone pen without the cap;

FIG. 23 is a perspective view of the cap;

FIG. 24 is a front view of the cap, with the opposing rear side being a mirror image thereof;

(Continued)

FIG. 25 is a left side view of the cap, with the opposing right side being a mirror image thereof;
 FIG. 26 is a top plan view of the cap; and,
 FIG. 27 is a bottom plan view of the cap.
